Primary Examiner — Susan Bennett Hattan*Assistant Examiner* — Janice Hallmark(74) *Attorney, Agent, or Firm* — Kilpatrick Townsend & Stockton LLP(57) **CLAIM**

The ornamental design for input accessory for a mobile phone, as shown and described.

DESCRIPTION

FIG. 1 is a perspective view of an input accessory for a mobile phone showing my new design;

FIG. 2 is a top plan view thereof;

FIG. 3 is a bottom plan view thereof;

FIG. 4 is a second perspective view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines in the drawings illustrate portions of the input accessory for a mobile phone which form no part of the claimed design.
